Primary Examiner — Elizabeth Albert(74) *Attorney, Agent, or Firm* — Lempia Summerfield
Katz LLC(57) **CLAIM**

The ornamental design for a “writing instrument”, as shown and described.

DESCRIPTION

FIG. 1 is a front, bottom, and right side perspective view of our new design for a writing instrument with a writing tip exposed for use.

FIG. 2 is a front view of the writing instrument of FIG. 1. FIG. 3 is a rear view of the writing instrument of FIG. 1. FIG. 4 is a right side view of the writing instrument of FIG. 1, the left side view being identical thereto.

FIG. 5 is a top view of the writing instrument of FIG. 1.

FIG. 6 is a bottom view of the writing instrument of FIG. 1; and,

FIG. 7 is a front view of the writing instrument of FIG. 1 with the writing tip covered.

The broken lines in FIGS. 1-4 and 6-7 are included to show portions of the writing instrument that form no part of the claimed design.

1 Claim, 3 Drawing Sheets(56)
